EXERCISING AND STRETCHING DEVICE

John J. Lee, Los Angeles, Calif.

Application December 12, 1938, Serial No. 245,083

1 Claim. (Cl. 272—80)

This invention relates to an exercising and stretching device for improving nerve, joint and circulatory conditions in the cervical, cranial and upper thoracic regions of the human body.

5 Abnormal cervical conditions, such as subluxations of cervical vertebra and contracted ligaments, in certain cases interfere with circulation and nerve function in such a way as to produce various ailments, among them headaches, disorders of hearing and abnormal brain 10 conditions. It is an object of this invention to provide a means whereby anyone troubled with such conditions can aid himself or herself to relieve them.

15 Other objects, advantages and features of the invention may hereinafter appear.

Referring to the accompanying drawing, which illustrates what is at present deemed to be a preferred embodiment of the invention,

20 Fig. 1 is an elevational view, slightly in perspective, showing the device per se except that a fragment of the support therefor is included in the view.

Fig. 2 is a like view, on a somewhat smaller 25 scale, showing the device in its operative position.

Referring in detail to the drawing, the main parts of the device are a head harness 10, a flexible member 11, a hanger 12 for suspending the device from an overhead support 13, and the 30 upper member 17 and lower member 15, the two latter members serving as a means to connect said member 11 with said hanger 12 and head harness 10 in order that said member may be utilized manually to exert varying lifting force 35 upon said head harness.

By preference and as shown, the members 17 and 15 for guiding the cord or other flexible member 11, are constructed as follows: The upper member 17 comprises a stiff wire having 40 at its upper end a rightangularly shaped hook 18 furnished with a sharp, downwardly directed spur 19 at its extremity. Adjacent to its lower end said wire has a circularly coiled portion 21 which grips the grooved periphery of a guide 22. 45 Although said guide 22 is a sheave in the sense of guiding and aiding to support weight by means of the member 11, yet said member does not engage the grooved part of the guide but, instead, passes loosely through the smooth, beveled aperture 23 of said guide. Below its coil 21 the wire 17 is furnished at its lower extremity with an eye 24 to which one end of the flexible member or cord 11 is attached. When the device is in its operative position the portion thereof superjacent 50 to its coiled portion 21 extends vertically upward,

and the portion thereof immediately below said coiled portion extends vertically downward. That is to say, the portions of the wire adjacent to its said coil are continued in opposite directions, and the coil extends through a complete, 5 unbroken circumference, thus producing a very stable seat by which the guide 22 is securely locked in place.

The lower cord guiding member 15 likewise has a coiled stiff wire portion 24 which grips a guide 10 or pulley-like member 25 having through it a smoothly rounded aperture 26 through which the member 11 freely runs. The coiled portion of the lifting member 15 is formed with intermediate crossed limbs 27, each of said limbs having a 15 terminal portion 28 which is directed toward that of the other in order that an upper loop 30 with which the head harness is furnished, may thus be supported.

Said head harness loop 30 forms part of an 20 endless band, its lower part 31 being adapted to fit under the occiput when the head harness is in place. At the juncture of the loops 30 and 31 a U-shaped band 32 has its upper ends externally attached by means of stitching 33, leaving the 25 inner surface of the main band smooth and comfortable. The looped band portions 31 and 32 are sufficiently broad to press comfortably against the occiput and submaxillary regions even when considerable upward pressure is applied by means 30 of said bands.

The assembly of hanger elements 11, 12, 14 and 15 may, if desired, be made as a separate article of manufacture to be used in conjunction with other types of head harness than that shown and 35 described.

The spur 19 provides a secure anchorage for the hanger member 12.

The auxiliary loop 32, which underlies the chin when the device is in use, is made to extend down 40 farther than the loop 33 which passes below the occiput and which forms a part of the endless main loop. Hence, when upward traction is applied to the head harness by means of the flexible member 11, the normal posture of the head is not 45 disturbed.

As shown in Fig. 1, the member 11 has an anchored end run 35 which is tied to the eye 24, a middle run 36, (the portion of the member made up by said runs 35 and 36 passing loosely 50 through the lower guide 25) and after said member passes through the upper guide 22 it terminates in a free end portion 37 which extends down to a level where it may readily be grasped and pulled upon by the person wearing the head 55

harness. Therefore the user can, by pulling upon the cord portion 37, apply a moderate lifting force to his head sufficient to relax the tissues of his neck, or by exerting a stronger pull upon the cord a positive stretching of the neck tissues may be produced.

The value of this exercise may be increased by pulling upon the cord first with one hand and then with the other and also by tilting the head 10 from front to back or from side to side while operating the cord.

As the muscles of the arms have their origins, in part, in the basal portion of the cervical region, the use of the arms in pulling upon the cord aids in improving the circulation through the neck simultaneously with the beneficial effects of the varying lifting force being applied to the head.

By using the centrally apertured peripherally 20 grooved guides 22 and 25, of a non-rotatable character and held in place by wire coils extending around them, the cost of manufacture is lowered to such an extent as to place the device,

as to cost, among the inexpensive type of novelties.

I claim:

In a device of the kind described, a single piece of wire bent into a hook at one end, an eye at its 5 opposite end and a substantially circular coil adjacent to the end thereof provided with said eye, a circular guide having through it a central aperture and having a peripheral groove around it, said wire coil being seated in said groove 10 thereby securing said guide to said wire, said coil completely encircling said guide and the wire portions adjacent thereto being continued in opposite directions, a flexible member which extends loosely through said aperture of said guide 15 and has one of its ends secured to said eye, and a lifting member for supporting a head harness, said lifting member having an aperture through which loosely passes the portion of said flexible member between said eye and the aperture 20 through said guide.

JOHN J. LEE.
